UNITED STATES PATENT OFFICE.

DORSETTE A. DAVISON, OF RICHMOND, VIRGINIA.

AEROPLANE.

1,038,306.

Specification of Letters Patent. Patented Sept. 10, 1912.

Application filed December 14, 1911. Serial No. 665,596.

To all whom it may concern:

Be it known that I, DORSETTE A. DAVISON, a citizen of the United States, and a resident of Richmond, in the county of Henrico and State of Virginia, have made certain new and useful Improvements in Aeroplanes, of which the following is a specification.

My invention relates to improvements in aeroplanes, and it consists more particularly in a novel form of main sustaining planes or wings.

An object of my invention is to provide wings or planes which will have the maximum sustaining effect for the surface used.

A further object of my invention is to provide means for maintaining equilibrium.

A further object of my invention is to provide a novel form of plane which overcomes the disastrous effects of side movement due to the peculiar formation of the sustaining wings.

Other objects and advantages will appear in the following specification, and the novel features of the device will be particularly pointed out in the appended claims.

My invention is illustrated in the accompanying drawings forming part of this application in which—

Figure 1 is a perspective view of an aeroplane constructed according to my invention, Fig. 2 is a plan view of the main sustaining wings, Fig. 3 is a section along the line 3—3 of Fig. 2, and Fig. 4 is a section along the line 4—4 of Fig. 2.

Referring now particularly to Figs. 2, 3 and 4, I have shown therein a pair of curved wings A and B of the shape shown in the drawings. It will be noticed that the front portions *a* and *b* of the wings are bent on an arc toward the rear as shown in Fig. 2, and they are also curved in lateral arcs as shown in Fig. 3. The rear edges *a*² and *b*² have a greater rearward curvature as shown in Fig. 2, and they also have greater lateral curvature, *i. e.*, the radii of curvature in both the rearward and the lateral directions of the edges *a*² and *b*² is less than the forward edges *a* and *b*. Consider now a section along the line 4—4, such a section would appear like that in Fig. 4. The wing B, therefore, is really made up of two arched sections, *b*^x and *b*^y. Since the wing A is similar to the wing B, it is also made up of two sections similar to the sections *b*^x and *b*^y. In order to support the wings, I

provide a series of ribs like those shown at R in Figs. 2, 3 and 4. These ribs are secured at one end to a central keel, or "breastbone," K. At the forward end of the keel is a flexible fin F of triangular shape, the forward end of which is connected by means of flexible cords C with pulleys P on the planes or wings and thence extend into the car M where they can be manipulated by the operator. In the illustration the car is shown as suspended from the keel, or "breastbone." This view is merely diagrammatic and is not intended to picture an actual device. The propeller R is designed to be placed in the rear of the car underneath the keel, and the rudder S to be carried at the rear end of the keel F in the manner shown in Fig. 1.

From the foregoing description of the various parts of the device, the operation thereof may be readily understood.

The two pockets in each wing, such as those shown at *b*^x and *b*^y, tend to cause the wings to be supported at four points since the air tends to exert an upward lift at the highest portion of each pocket. When the device is in motion as shown in Fig. 1, the air strikes the under side of the wings. It will be noted from Fig. 4 that the air will tend to bank up against the planes so as to cause a maximum lifting effect. In case the aeroplane should start to fall sidewise, *i. e.*, toward the end of one wing, the presence of the keel or "breastbone" will tend to automatically right the device since it will cause the banking of the air under that wing which is tipped downwardly. In order to further balance the device, I provide the flexible fin F. The forward part of this fin may be pulled rearwardly and upwardly so as to warp the surface of the fin toward one side or the other of the keel. This causes the righting of the device through the action of the air upon the fin. The fin has a double purpose of being acted on by the air and of cutting off the air from the wing behind it.

I claim:

1. In an aeroplane, a central keel or breastbone, a pair of wings secured thereto and extending laterally therefrom, each of said wings curving laterally in an arc, and each wing consisting of two arched portions from front to rear, and the forward edge of each wing having a greater radius of lateral curvature than the rear edge.

2. In an aeroplane, a central keel or "breastbone," a pair of wings secured thereto and extending laterally therefrom, each of said wings curving laterally in an arc, and each wing consisting of two portions arched from front to rear, the forward edge of each wing having a greater radius of lateral curvature than the rear edge, a flexible, triangular fin secured to the front edge of said keel, and flexible cords secured to said fin and arranged to bend the latter in a rearward and upward direction.
3. In an aeroplane, a central keel or

"breastbone," a pair of wings extending laterally therefrom, each of said wings being curved in a lateral direction and having two arc-shaped portions from front to rear, the front edge of each wing being curved to the rear and the rear edge of each wing being curved to the rear on a less radius than the front edge.

DORSETTE A. DAVISON.
